UNITED STATES PATENT OFFICE

149,924

DESIGN FOR A BRACELET OR SIMILAR ARTICLE

Otis R. Angell, Wollaston, Mass.

Application January 15, 1946, Serial No. 125,551

Term of patent 7 years

(Cl. D45—4)

To all whom it may concern:

Be it known that I, Otis R. Angell, a citizen of the United States of America, residing at Wollaston, in the county of Norfolk and Commonwealth of Massachusetts, have invented a new, original, and ornamental Design for a Bracelet or Similar Article, of which the following is a specification, reference being had to the accompanying drawing, forming a part thereof.

Fig. 1 is a side elevation of a bracelet, embodying my new design;

Fig. 2 is an edge view of the bracelet of Fig. 1; and

Fig. 3 is a top plan view on a reduced scale of the bracelet in a flattened position.

The characteristic feature of my design for the cuff bracelet shown resides in the overlapping concentric circles microscopically scratched on

the polished surface of the bracelet contiguous to the outer edges thereof.

I claim:

The ornamental design for a bracelet or similar article, substantially as shown and described.

OTIS R. ANGELL.
